(57) **CLAIM**

The ornamental design for a folding ear wash basin as shown and described.

DESCRIPTION

FIG. 1 is a perspective view of a folding ear wash basin showing our new design;

FIG. 2 is a folded state of the folding ear wash basin shown in FIG. 1;

FIG. 3 is a front view of FIG. 1;

FIG. 4 is a back view thereof;

FIG. 5 is a left view thereof;

FIG. 6 is a right view thereof;

FIG. 7 is a top view thereof; and,

FIG. 8 is a bottom view thereof.

The broken lines shown in the figures depict portions of the folding ear wash basin that do not form part of the claimed design.

1 Claim, 8 Drawing Sheets
